US0D1047925S

(12) **United States Design Patent** (10) **Patent No.:** **US D1,047,925 S**
(45) **Date of Patent:** **** Oct. 22, 2024**

(54) **ADAPTER**

(71) Applicant: **GuangDong LDNIO Electronic Technology Co., Ltd.**, Foshan (CN)

(72) Inventor: **Yanmei Liao**, Foshan (CN)

(73) Assignee: **GuangDong LDNIO Electronic Technology Co., Ltd.**, Foshan (CN)

(**) Term: **15 Years**

(21) Appl. No.: **29/869,954**

(22) Filed: **Jan. 13, 2023**

(30) **Foreign Application Priority Data**

Nov. 29, 2022 (CN) 202230799371.6

(51) **LOC (14) Cl.** **13-03**

(52) **U.S. Cl.**

USPC **D13/137.2; D13/137.1; D13/107**

(58) **Field of Classification Search**

USPC D13/107, 123, 133, 137.1, 137.2, 137.3,

D13/137.4, 138.1, 138.2, 139.1, 139.2,

D13/139.4, 139.5, 139.6, 139.7, 139.8,

D13/146, 147

(57) **CLAIM**

The ornamental design for an adapter, as shown and described.

DESCRIPTION

FIG. 1 is a top, front, right side perspective view of an adapter of the present disclosure;

FIG. 2 is a bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines shown in the drawings depict portions of the adapter that form no part of the claimed design.

1 Claim, 8 Drawing Sheets
